UNITED STATES PATENT OFFICE.

JOHN PFEIFER, OF PHILADELPHIA, PENNSYLVANIA.

HANDLE FOR SHOVELS.

SPECIFICATION forming part of Letters Patent No. 364,039, dated May 31, 1887.

Application filed November 16, 1886. Serial No. 219,030. (No model.)

To all whom it may concern:

Be it known that I, JOHN PFEIFER, a citizen of the United States, residing in the city and county of Philadelphia, State of Pennsylvania, have invented a new and useful Improvement in Handles for Shovels, Spades, Scoops, Forks, &c., which improvement is fully set forth in the following specification and accompanying drawings, in which—

10 Figure 1 represents a rear view of a shovel embodying my invention. Fig. 2 represents a side elevation of the grip portion thereof. Fig. 3 represents a section in line *x x*, Fig. 1. Fig. 4 represents a section in line *y y*, Fig. 1. Fig. 5 represents a section in line *z z*, Fig. 1.

Similar letters of reference indicate corresponding parts in the several figures.

My invention consists of a shovel, scoop, &c., having a metallic handle of tubular form, the same being strong and durable.

It also consists in forming the arms of the grip integral with the handle of the shovel, &c., whereby said arms, and consequently the grip, are rendered strong and durable.

25 Referring to the drawings, A represents the blade of a shovel, scoop, &c., B the handle, and C the grip thereof.

The handle B is constructed in tubular form of wrought metal, and has the pad or tang D integral therewith, said pad or tang being riveted to the blade A.

30 E represents arms which are continuous of the handle B, at the end opposite to the tang and integral therewith and supporting the grip C, it being noticed that said arms project from the handle and are crimped in the direction of their length, as at F.

In order to close the ends of the handle, short pieces of wood are inserted in said ends, 40 as at G, and secured by rivets or other suitable means.

It will be seen that the handle as constructed is strong and durable, and will not crack, or

splinter, as is the case with a wooden handle. The crimped arms E are likewise strong and durable, and as said arms are integral with the handle it is evident that they are enabled to endure the strain to which they are subjected.

The pad or tang is also made integral with the handle, thus rendering the connection of the same of a firm and durable nature, it being seen that the handle, arms, and pad or tang are one continuous piece of metal without break in the length of the same, producing superior results. When desired, the pad or tang may be welded or otherwise secured to the handle; but the integral pad or tang is preferred, as a single piece of wrought metal may be employed to form the handle, arms, and pad or tang.

Having thus described my invention, what I claim as new, and desire to secure by Letters Patent, is—

1. A shovel having a tubular stock with arms formed on opposite sides of one end of said stock integral therewith, as described.

2. A shovel having a tubular stock, a tang, and arms formed of opposite sides of the end of said stock, said tang and arms being integral with said stock, substantially as described.

3. A shovel having a tubular stock, with tang and grip-arms integral therewith, and a grip secured to said grip-arms, the grip-arms being formed of opposite sides of one end of the tubular stock, all substantially as described.

4. A shovel or scoop formed of a tubular handle, with grip-supporting arms integral therewith, a grip, a blade, a tang, and fillings in the ends of said tubular handle, all substantially as and for the purpose set forth.

JOHN PFEIFER.
